UNITED STATES PATENT OFFICE.

JOHN H. WALLSTROM, OF ROCKFORD, ILLINOIS.

LIMEKILN.

SPECIFICATION forming part of Letters Patent No. 380,706, dated April 10, 1888.

Application filed August 18, 1887. Serial No. 217,260. (No model.)

To all whom it may concern:

Be it known that I, JOHN H. WALLSTROM, a subject of the King of Sweden, and residing in the city of Rockford, county of Winnebago, 5 and State of Illinois, have invented certain new and useful Improvements in Limekilns, of which the following is a specification.

This invention relates to a class of lime-burning kilns known as the "perpetual kiln," 10 and it is of a variety in which the fuel-combustion chamber is separated from the chamber containing the limestone to be burned, and in which the gases produced in the fuel-combustion chamber pass through flues into 15 the chamber containing the limestone, and in connection therewith is ignited to burn the stone to lime.

The object of this invention is to improve 20 this class of kilns to render them more efficient, and to this end I have designed and constructed the kiln represented in the accompanying drawings, which I now proceed to describe, and in which—

Figure 1 is an elevation of a kiln embodying my invention. Fig. 2 is a vertical central section on dotted line *a* on Fig. 5. Fig. 3 is a vertical section on dotted line *b* on Fig. 9. Fig. 4 is an end elevation of the fuel-combustion chamber. Fig. 5 is a horizontal section 30 on dotted line *c* on Fig. 2. Fig. 6 is a horizontal section on dotted line *d* on Fig. 2. Fig. 7 is a horizontal section on dotted line *e* on Fig. 2. Fig. 8 is a horizontal section on dotted line *f* on Fig. 2, and Fig. 9 is a horizontal section on dotted line *g* on Fig. 2.

The kiln-stack is preferably of circular form in plan, with lateral projections 1, extending on opposite sides of its base portion, forming the fuel-combustion chambers 2, each of which 40 is provided with an inclined fire grate, 3, in mill-stair form, the several grate-bars of which are provided centrally with vertical supports. The outer portions of the lateral projections 1 are supported on the several sides of their 45 external angles by vertical clamping bars 4, held in place in the usual manner by means of holding-bolts 5, built in the walls of the chambers.

Fuel-induction ports 6 are formed in the 50 upper surface of the lateral projections over the outer portion of the fire-grates, and these induction-ports are provided with removable

covers to admit the fuel which is dropped through the ports onto the fire-grates, and the covers put in place prevent the escape of gas 55 through the ports.

Gas flues 7 rise from the inner end of the combustion-chambers and connect with annular gas-flues 8, which extend around or nearly around the furnace-chamber 9 of the kiln 60 within the furnace-walls, and vertical gas-flues 10 connect the annular flues with a series of radial gas-flues, 11, which extend through the furnace-walls and open upward into the furnace. A series of radial air-flues, 12, extend 65 through the furnace-walls above the gas-flues 11 and open upward into the furnace above the inner openings of the gas-flues.

Metallic bands 13 surround the furnace-walls above and below the outer end openings 70 of the radial gas and air flues, and doors 14 are made to slide between the metallic bands to open or close the external openings of the radial flues to regulate the admission of air to mix with the gases rising from the combustion-chambers through the flues into the furnace, to insure the most perfect combustion 75 of the gases within the furnace.

The radial flues also serve to permit the inspection of the interior of the furnace at 80 the points of greatest combustion of the gases, and permit the attendant to stir the contents of the furnace by means of suitable stirring implements passed through the radial flues.

A central core, 15, is built in the base portion of the furnace, and in this instance the core rises to about the height of the air-flues 85 to narrow the space for the passage of the limestone between the inner walls of the furnace and the core at the point of greatest combustion of the gases, which is a favorable construction when the limestone to be burned is broken quite fine; but when it is desirable to burn the lime in larger stones I prefer that the core shall not rise above the under face of 90 the air-flues, as represented in the dotted lines in Figs. 2 and 3, to enable the attendant to stir the contents of the furnace above the core.

The portion 16 of the combustion-chamber under the grate-bars forms the ash-pit, and 100 the external openings provided with doors 17 permits the attendant to stir or rake the fire through the grate-bars and remove the ashes from the pit, and by means of registers

in the doors to the ash-pit the admission of air to the combustion-chamber under the grate-bars may be regulated to produce the greatest amount of gas to be ignited in its passage 5 to the furnace.

Draw-openings 18 are formed in the base portion of the kiln on opposite sides thereof, through which the burned lime is drawn from the kiln, and doors 19 are provided to close 10 their external openings.

The central section, 20, of the kiln is preferably built in hexagonal form in section, and is bound at proper intervals by beams 21, ship-lapped and bolted at their crossings.

15 The upper section, 22, of the kiln is a truncated hexagonal pyramid in outline, and is provided at its base with a door, 23, through which the limestone to be burned is fed into the kiln.

The walls of the kiln may be made of any 20 suitable material, such as stone or brick, but preferably of stone and brick; and the inner surfaces of all parts of the kiln exposed to great heat are lined with fire-proof brick, and such linings are mainly represented in the 25 drawings in the black shadings.

Non-conducting chambers 24, surrounding the furnace, are formed in the vertical walls of the lower and middle sections, and these 30 chambers are filled with sand or other suitable material, and serve to obstruct radiation and also to prevent bursting of the walls.

In the use of my improved kiln the limestone to be burned is first broken to a size that will prevent clogging or choking in its passage 35 over the center core, 15, and is then passed through the door 23 in the upper section into the kiln. The fuel, if not previously placed, is then dropped through the induction-ports 6 onto the inclined fire-grates, and is then burned 40 in a manner to produce the greatest amount of gas, which passes through the flues as indicated by the arrows, and in its passage to the furnace is ignited, and is supplied with the requisite amount of atmospheric air to insure 45 complete combustion, to produce the greatest amount of heat in its passage through the stone in the furnace, which will be rapidly converted into lime, to be withdrawn from the kiln through the draw holes.

50 The withdrawal of the lime permits the contents of the furnace to settle, to carry the

burned stone or lime to the bottom of the kiln and the unburned stone to a position in the furnace where the heat produced by the combustion of the gases is most intense.

In this construction of kiln the lime, ashes, and cinders of the fuel are separated, by which a much purer article of lime is produced, and the labor of separating the ashes and cinders from the lime is avoided.

In the use of my improved kiln any of the ordinary fuels may be used; but fuels which will produce the greatest amount of gas—such as bituminous coals, peat, or gas-producing varieties of wood, either separately or combined—are preferred.

I claim as my invention—

1. In a limekiln, the combination of a furnace, a central core in the base of the furnace, combustion-chambers, an annular gas-flue, 70 flues connecting the combustion-chambers and annular gas-flue, radial flues to the furnace, and flues connecting the annular flue and radial flues, substantially as and for the purpose set forth.

2. The combination of the furnace, combustion-chambers, a system of flues consisting of an annular flue, radial flues to the furnace, and flues connecting the annular flue with the radial flues and with the combustion-chambers, 80 and a series of radial air-flues to the furnace above the gas-flues, opening into the furnace, substantially as and for the purpose set forth.

3. The combination of a furnace, combustion-chambers, a system of gas-flues consisting of an annular gas-flue, radial flues to the furnace, and flues connecting the annular flue with the radial flues and with the combustion-chambers, and draw-openings, substantially as and for the purpose set forth.

4. The combination of a furnace, combustion-chambers, a system of gas-flues, substantially as shown and described, between the combustion-chambers and furnace, and non-conducting chambers surrounding the furnace 95 within the furnace-walls, substantially as and for the purpose set forth.

JOHN H. WALLSTROM.
